UNITED STATES PATENT OFFICE

93,051

DESIGN FOR A FURNITURE PEDESTAL BASE

Arthur R. Schwarzkopf, Chicago, Ill., assignor to Theo. A. Kochs Company, Chicago, Ill., a corporation of Illinois

Application March 5, 1934, Serial No. 50,950

Term of patent 7 years

To all whom it may concern:

Be it known that I, ARTHUR R. SCHWARZKOPF, a citizen of the United States, residing at Chicago, in the county of Cook, and State of Illinois, have invented a new, original, and ornamental Design for a Furniture Pedestal Base, of which the following is a specification, reference being had to the accompanying drawing forming part thereof, wherein—

The figure is a perspective view of a furniture pedestal base showing my new design.

I claim:
The ornamental design for a furniture pedestal base, as shown.

ARTHUR R. SCHWARZKOPF.
